9426

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A CHILD'S COSTUME.

SPECIFICATION forming part of Design No. 15,621, dated December 16, 1884.

Application filed September 12, 1884. Term of patent 34 years.

To all whom it may concern:

Be it known that I, CATHERINE O'HARA, of the city, county, and State of New York, have invented and produced a new and original Design for a Pattern of a Child's Costume, (numbered 9,426;) and I do hereby declare that the engraved prints accompanying this specification convey to any one accustomed to using paper patterns a clear understanding of how a garment made up by the pattern will appear.

The design shows a loose-fitting body-front that displays a box-plait down its center, a loose-fitting body-back that also displays a box-plait down its center, a skirt exhibiting

single wide side plaits alternating with clusters of narrow side plaits, a sash surrounding the top of the skirt and exhibiting a bow effect at the back, coat sleeves, and a standing collar.

What I claim as my invention, and desire to secure by Letters Patent, is-

The design for a child's costume, as shown in the engraved prints accompanying this specification.

CATHERINE O'HARA.
